UNITED STATES PATENT OFFICE.

OSCAR F. GRANT, OF PITTSBURG, PENNSYLVANIA, ASSIGNOR TO THE STANDARD MANUFACTURING COMPANY, OF SAME PLACE.

DESIGN FOR A CRADLE FOR BATH-TUBS.

SPECIFICATION forming part of Design No. 20,179, dated September 30, 1890.

Application filed July 12, 1890. Serial No. 358,577. Term of patent 7 years.

To all whom it may concern:

Be it known that I, OSCAR F. GRANT, a citizen of the United States, residing at Pittsburgh, in the county of Allegheny and State of Pennsylvania, have invented certain new Designs for Cradles for Bath-Tubs; and I do hereby declare the following to be a full, clear, and exact description of the invention, reference being had to the accompanying drawing, which forms part of this specification.

This invention has relation to designs for ornamental bath-tub cradles or supporting-stands; and it consists of a cradle or stand having the ornamental features hereinafter described, and shown in the accompanying illustration, the latter being a perspective view of the cradle or stand applied to a bath-tub.

The stand or cradle is of substantially rectangular form, corresponding in general outline to the shape of a bath-tub, and comprises the suitably-ornamented guard or fender A, the fanciful legs B, and the cornice C.

What I claim, and desire to secure by Letters Patent, is—

The design for a bath-tub cradle or supporting-stand, consisting of the guard or fender A, the legs or supports B, and the cornice C, substantially as shown and described.

In testimony that I claim the foregoing I have hereunto set my hand this 13th day of May, 1890.

OSCAR F. GRANT.
